United States Patent Office

Des. 201,000
Patented May 4, 1965

201,000

SOAP DISH

Hy H. Kobrin, 832 N. 8th St., Reading, Pa.

Filed Aug. 1, 1963, Ser. No. 76,066

Term of patent 3½ years

(Cl. D4—3)

Fig. 1.

Fig. 2.

Fig. 3.

FIG. 1 is a top view of a soap dish, showing my new design, and

FIG. 2 is a side view, and FIG. 3 is a perspective view thereof.

The bottom is flat and plain.

The bar of soap shown in dotted outline is included for illustrative purposes only.

I claim:

The ornamental design for a soap dish, substantially as shown and described.
